DESIGN FOR A CROWN CAP REMOVER

Mauritz C. Ranseen, Minneapolis, Minn.

Application September 27, 1944, Serial No. 115,481

Term of patent 14 years

(Cl. D44—29)

To all whom it may concern:

Be it known that I, Mauritz C. Ranseen, a citizen of the United States, residing at Minneapolis, county of Hennepin, and State of Minnesota, have invented a new, original, and ornamental Design for a Crown Cap Remover, of which the following is a specification, reference being had to the accompanying drawing, forming part thereof, and in which

Figure 1 is a side view of a crown cap remover showing my new design;

Figure 2 is a top view of Figure 1;

Figure 3 is a front view of Figure 1.

I claim:

The ornamental design for a crown cap remover, substantially as shown.

MAURITZ C. RANSEEN.
